United States Patent Office.

JOHN H. BROWN, OF GENESEO, NEW YORK.

Design No. 2,852, dated December 31, 1867.

DESIGN FOR A MOULDING FOR PICTURE-FRAMES.

The Schedule referred to in these Letters Patent and making part of the same.

TO ALL WHOM IT MAY CONCERN:

Be it known that I, JOHN H. BROWN, of Geneseo, in the county of Livingston, and State of New York, have originated or invented a new Design for Mouldings for Making Picture-Frames, &c.; and I do hereby declare that the following is a full and exact description thereof, reference being had to the accompanying drawings, making part of this specification.

The drawing represents a section or part of a moulding embodying the design.

The object is to produce an ornamental moulding as an article of manufacture, which is put into the market in suitable lengths, and from which pieces may be cut as desired, to form picture-frames and similar articles.

The design consists in making the face of the moulding rounding or convex in section, and providing it, at intervals, with ornamental offsets or shoulders, and lining it as hereinafter set forth.

As represented in the drawings, A is a section or part of a moulding, made rounding or convex in cross-section, as shown at a. The body of the moulding is grained, or cut with coarse or fine lines, longitudinally, as shown at b. At intervals the moulding is provided with large or small offsets or shoulders, c c.

Mouldings made after this design, have a pleasing appearance to the eye, the offsets or shoulders, in connection with the lining, giving a fine rustic effect.

What I claim as my invention, and desire to secure by Letters Patent, is—
The design for mouldings as herein set forth.

In witness whereof, I have hereunto signed my name in the presence of two subscribing witnesses.
